UNITED STATES PATENT OFFICE.

ALBERT E. SCHAAF, OF POUGHKEEPSIE, NEW YORK, ASSIGNOR TO F. I. A. T., A CORPORATION OF NEW YORK.

HOOD-CORNICE FOR AUTOMOBILES.

1,078,961.

Specification of Letters Patent. Patented Nov. 18, 1913.

Application filed January 28, 1913. Serial No. 744,629.

To all whom it may concern:

Be it known that I, ALBERT E. SCHAAF, a citizen of the United States, residing at Poughkeepsie, in the county of Dutchess and State of New York, have invented certain new and useful Improvements in Hood-Cornices for Automobiles, of which the following is a full, clear, and exact specification.

This invention relates to improvements in means for supporting the hinged hood employed to cover the engine of an automobile, and has particular reference to the construction of this support or hood cornice, whereby it constitutes a conduit and support for the electric ignition or starting or lighting wires now commonly employed in automobiles.

At the present time, it is quite difficult to produce a neat installation of wires for the electric devices used in conjunction with the engine, and especially such wiring as is required to be under the hood, such as the ignition wiring and also in some instances the wires leading to the head lights. This wiring should be protected from grease, oil and dirt, from jarring or vibration, and should also be condensed as much as possible so as not to interfere with access to other parts of the machine for adjustment or inspection.

According to this invention, the wires more particularly for the ignition and the head lights, if desired, can be carried in closed conduits formed in the hood cornice and attached to the dash, whereby there is formed a closed wire conduit in which the wires will be protected and at the same time the wires can be led to a junction box chamber located on the dash at the top of the hood cornice and closed by a cover. In connection with the bottom of the cornice conduit and formed in the horizontal hood strip carried on the chassis is an additional conduit for the wires leading to the head lights or for other purposes, such as a lighting generator, storage battery, etc. By means of the combined hood ledge, electric wire conduits and junction box with removable cover herein described, electric wiring can be put very largely out of sight and at the same time protected against deterioration and vibration, and simplify the appearance of the installation.

In the accompanying drawings, Figure 1

is a front elevation of a hood cornice embodying the invention; Fig. 2 is a side elevation partly in section; Fig. 3 is a section on the line 3—3 of Fig. 1; and Fig. 4 is a view of the cover for the junction box.

60

1 represents the chassis of a vehicle carrying the upright dash 2 and the horizontal hood strip 3, with which the hinged hood 4 contacts when it is closed. The hood 4 is composed of joined sections in any suitable manner as is well known and preferably hinged at the top to a rod 5 which may be fastened at the forward end to the radiator (not shown) and at the rear end to the dash 2 or to the hood cornice 7 as herein shown in Fig. 2. The hood cornice 7 as shown in front elevation in Fig. 1 consists of the hood supporting flange 8, with which the vertical edge of the hood engages, attaching lugs 9 for securing it to the dash 2 and a channeled recess 10 in its inner face adjacent the support constituting a wire conduit, and containing for example, wires 13. Either or both of the sides of the hood cornice body portion 7 may be provided with the conduits 10, which lead to the junction box receptacle 14 formed at the apex of the cornice, and closed by a removable cover 15. This receptacle 14 is comprised within the divided portions 16, 17 of the hood cornice, and the dash 2 and cover 15, and communicating directly with the channel or channels 10, so that the wires can be easily run through or pulled out without taking down the cornice. Within the junction box receptacle 14 the necessary or desired electrical fittings, such as outlet boxes, terminals, etc. as furnished by manufacturers will be installed, and these will all be readily accessible upon removing the cover 15 and protected when the cover 15 is in place. For carrying the wires horizontally to the forward lights, the horizontal hood strip 3 is provided with a channel 18, which communicates with the channel 10, so that the wires can be run directly from channel 10 to channel 18 to either head lights or such other devices as are desired.

90

From the foregoing description, it will be seen that by means of the improved hood cornice strip herein described, the electric wires can be housed and protected and at the same time the junction box receptacle is provided for housing and protecting the necessary electrical fittings for the wires,

and so arranged as to be accessible whenever necessary.

Various changes and modifications in the specific details of construction may be made without departing from the scope of the invention.

Having thus described my invention, I declare that what I claim as new and desire to secure by Letters Patent, is:—

- 10 1. An arched hood cornice comprising means for attachment to the dash or similar support, a channeled portion constituting a wire conduit, an outlet box connected to said conduit, and a hood supporting flange.
- 15 2. The combination with a dash, of a hood supporting cornice attached thereto, said cornice being arched and having a channeled portion constituting a wire conduit formed therein and closed by said dash.
- 20 3. The combination with a dash, of an arched cornice attached thereto comprising an outlet chamber, and a channeled side portion constituting a wire conduit communicating with said chamber, and a hood supporting flange carried by said cornice.
- 25 4. The combination with a dash, of an arched cornice strip carried thereby, and having a channel constituting a wire conduit in the side next the dash, and on the opposite side a hood supporting flange.
- 30 5. The combination with a dash, of an arched cornice strip comprising a channeled portion adjacent the dash constituting a wire conduit, said conduit opening into an enlarged outlet fitting chamber at the apex portion, and a removable cover plate for inclosing said chamber.
- 35 6. The combination with a vehicle frame, of a vertically projecting dash carried there-

by, an arched cornice strip comprising a channeled portion adjacent the dash constituting a wire conduit, said conduit opening into an enlarged outlet fitting chamber at the apex portion, and a horizontal hood strip carried by the frame and having a wire conduit channel communicating with said conduit in said cornice strip.

7. The combination with a vehicle frame carrying a vertically projecting dash and a hood base strip, of an arched cornice strip comprising a channeled base adjacent the dash constituting a wire conduit, said conduit communicating at the bottom with a similar conduit in said hood base strip, and a hood supporting flange carried by said cornice.

8. A hood cornice strip comprising an arched strip having its vertical portion channeled to constitute a wire conduit, and divided at its apex to form a junction box chamber communicating with said conduit, and a flange carried by said strip for supporting the edge of a hood.

9. A hood cornice strip comprising an arched strip having its vertical portion channeled to constitute a wire conduit, and divided at its apex to form a junction box chamber communicating with said conduit, and a flange carried by said strip for supporting the edge of a hood and closures for the opposite sides of said chamber.

In testimony whereof I affix my signature, in presence of two witnesses.

ALBERT E. SCHAAF.
